UNITED STATES PATENT OFFICE.

JOSEPH J. MARKOVICH, OF UNIONTOWN, PENNSYLVANIA.

QUICK-ACTION WRENCH.

1,147,181.

Specification of Letters Patent. Patented July 20, 1915.

Application filed January 11, 1915. Serial No. 1,599.

To all whom it may concern:

Be it known that I, JOSEPH J. MARKOVICH, a citizen of the United States, residing at Uniontown, in the county of Fayette and 5 State of Pennsylvania, have invented certain new and useful Improvements in Quick-Action Wrenches, of which the following is a specification.

This invention relates to certain new and 10 useful improvements in quick action wrenches.

The primary object of this invention is to provide a wrench after the manner of the well-known Stillson wrench but in which 15 the outer jaw may be quickly and easily shifted within the limitations of its movement without the employment of any turn nuts or other similar means.

A further object is to provide a quick 20 action Stillson-form of wrench that consists of but few parts and is cheap and inexpensive to manufacture although possessing great strength and serviceability.

A still further object is to provide a 25 pivoted housing upon a jaw member at the termination of the wrench handle whereby a coacting jaw member is slidably mounted for quick adjustment operatively opposed to the handle carried jaw.

30 With these general objects in view and others that will appear as the nature of the invention is better understood, the same consists in the novel combination and arrangement of parts hereinafter more fully described, illustrated in the accompanying drawings and set forth in the appended claims.

In the drawings forming a part of this 40 application and in which like-designating characters refer to corresponding parts throughout the several views, Figure 1 is a side elevation of the device with the housing thereof shown in section. Fig. 2 is an edge view of the wrench. Fig. 3 is a transverse 45 sectional view taken upon line III—III of Fig. 1, and Fig. 4 is a perspective view of the shiftable locking lever detached.

Referring more in detail to the drawings, 50 it will be noted that a handle member 10 is provided terminating at one end in the jaw 11 having a serrated face 12. A housing 13 has projecting ears 14 at one corner thereof and by which the housing is pivotally mounted to the jaw end of the handle and 55 adjacent one end of the jaw by means of a pin 15, it being noted that the adjacent cor-

ner of the handle end has a laterally projecting curved portion 16 which is received within a cut-out portion 17 of the housing between the said ears 14. The housing is 60 also provided with spaced fingers 18 at the opposite corner of the housing from the ears 14 and the shank 19 of the handle is freely positioned between the said fingers. A longitudinal passage or opening 20 is provided 65 through the said housing in which the shank 21 of the coöperating or outer jaw 22 is slidably mounted which latter jaw has a serrated face 23 coöperatingly positioned 70 opposing the handle jaw face 12. A slot 24 is provided through the outer curved side 25 of the housing communicating with the passage 20 thereof and a locking lever 26 is pivoted within the said slot upon a transversely extending pin 27 secured to the housing. 75 The jaw shank 21 is provided with teeth 28 upon one edge thereof adapted to be engaged by similar teeth 29 upon the adjacent end of the lever 26, while the said lever terminates at one end in a single 80 spaced tooth or finger 30 which engages a separate tooth of the jaw rack at a point outside of the housing so that the housing wall 31 at one end of the slot 24 is between the lever finger and the teeth 29 and engages 85 with one of the teeth 28 simultaneously with the engagement of teeth 29, it being noted that the engaging end of the finger 30 is of greater width than either the lever or the shank 21 and teeth 28 and being also 90 greater than the width of the said slot 24. A handle 32 is provided upon the lever at the end thereof opposite the finger 30, while a spring 33 having one end thereof secured 95 as at 34 within the housing slot normally engages said lever handle for retaining the lever tooth in engagement with the jaw shank teeth.

It will thus be seen that a quick action wrench is provided in which the jaw 22 may be quickly shifted by releasing the locking lever while the two jaws are then readily placed in engagement with the work by slightly rocking the housing upon its pivotal connection with the wrench handle. For disengaging the wrench from the work the lever handle 32 is pressed inwardly which releases the outer jaw 22 so that the wrench is readily removed from the work.

While the form of the invention herein 110 shown and described is what is believed to be the preferred embodiment thereof, it is

nevertheless to be understood that minor changes may be made without departing from the spirit and scope of the invention as claimed.

5 What I claim as new is:—

1. A device of the class described comprising a handle terminating in a serrated jaw, a housing pivoted to the said jaw end of the handle and having a longitudinal 10 opening therethrough, and a side slot communicating with the said opening, a shiftable jaw oppositely arranged with respect to said handle jaw and having a toothed shank slidably mounted in said housing 15 opening, a lever pivotally mounted within the said slot and having a toothed inner portion in normal engagement with the teeth of the said rack, a projecting toothed finger at one end of the said lever positioned exteriorly of the housing and normally engaging a tooth of the said rack, and resiliently 20 normal positioning means secured to the said housing within the said slot and being in constant engagement with the said locking 25 lever.

2. A device of the class described comprising in combination with a shiftable housing having an opening therethrough, and a side slot communicating with the said opening, a jaw shank slidably mounted through the 30 said opening and having side teeth adjacent the said slot, a locking lever pivoted within the said slot and having a toothed portion normally projecting within the housing opening in engagement with the said shank 35 teeth, and a projecting toothed finger at one end of the lever of greater width than and spaced from the toothed portion of the lever and being in normal contact with a tooth of the shank exteriorly of the housing 40 and upon an opposite side of the end of the housing from the afore-mentioned teeth of the lever.

In testimony whereof I affix my signature in presence of two witnesses.

JOSEPH J. MARKOVICH.
